(57) **CLAIM**

The ornamental design for a climb and crawl activity playset, as shown and described.

DESCRIPTION

FIG. 1 is a front perspective view of component 1 of a climb and crawl activity playset, showing my new design; FIG. 2 is a rear perspective view of component 1 thereof; FIG. 3 is a front view of component 1 thereof; FIG. 4 is a rear view of component 1 thereof; FIG. 5 is a left side view of component 1 thereof; FIG. 6 is a right side view of component 1 thereof; FIG. 7 is a top view of component 1 thereof; FIG. 8 is a bottom view of component 1 thereof; FIG. 9 is a front perspective view of component 2 thereof; FIG. 10 is a rear perspective view of component 2 thereof; FIG. 11 is a front view of component 2 thereof; FIG. 12 is a rear view of component 2 thereof; FIG. 13 is a left side view of component 2 thereof; FIG. 14 is a right side view of component 2 thereof; FIG. 15 is a top view of component 2 thereof; FIG. 16 is a bottom view of component 2 thereof; FIG. 17 is a front perspective view of component 3 thereof; FIG. 18 is a rear perspective view of component 3 thereof; FIG. 19 is a front view of component 3 thereof; FIG. 20 is a rear view of component 3 thereof; FIG. 21 is a left side view of component 3 thereof; FIG. 22 is a right side view of component 3 thereof; FIG. 23 is a top view of component 3 thereof; FIG. 24 is a bottom view of component 3 thereof; FIG. 25 is a front perspective view of component 4 thereof; FIG. 26 is a rear perspective view of component 4 thereof; FIG. 27 is a front view of component 4 thereof; FIG. 28 is a rear view of component 4 thereof; FIG. 29 is a left side view of component 4 thereof; FIG. 30 is a right side view of component 4 thereof; FIG. 31 is a top view of component 4 thereof; FIG. 32 is a bottom view of component 4 thereof; FIG. 33 is a front perspective view of component 5 thereof; FIG. 34 is a rear perspective view of component 5 thereof; FIG. 35 is a front view of component 5 thereof; FIG. 36 is a rear view of component 5 thereof; FIG. 37 is a left side view of component 5 thereof; FIG. 38 is a right side view of component 5 thereof; FIG. 39 is a top view of component 5 thereof; FIG. 40 is a bottom view of component 5 thereof; FIG. 41 is a front perspective view of component 6 thereof;

(Continued)

FIG. 42 is a rear perspective view of component 6 thereof;
 FIG. 43 is a front view of component 6 thereof;
 FIG. 44 is a rear view of component 6 thereof;
 FIG. 45 is a left side view of component 6 thereof;
 FIG. 46 is a right side view of component 6 thereof;
 FIG. 47 is a top view of component 6 thereof;
 FIG. 48 is a bottom view of component 6 thereof;
 FIG. 49 is its combined state diagram thereof;
 FIG. 50 is its combined state diagram thereof;
 FIG. 51 is its combined state diagram thereof;
 FIG. 52 is its combined state diagram thereof; and,
 FIG. 53 is its combined state diagram.
